UNITED STATES PATENT OFFICE

161,205

SERVING PLATTER OR SIMILAR ARTICLE

Le Roy H. Raleigh, Ogden, Utah

Application May 20, 1950, Serial No. 10,070

Term of patent 14 years

(Cl. D44—10)

To all whom it may concern:

Be it known that I, Le Roy H. Raleigh, a citizen of the United States, and a resident of the city of Ogden, in the county of Weber and State of Utah, have invented a new, original, and ornamental Design for a Serving Platter or Similar Article, of which the following is a specification, reference being had to the accompanying drawing, forming a part thereof.

On the drawing:

Figure 1 is a plan view of the serving platter or similar article, showing my new design;

I claim:

The ornamental design for a serving platter or similar article, as shown.

LE ROY H. RALEIGH.
